UNITED STATES PATENT OFFICE

JOHN P. ANDERSON, OF KOPPEL, PENNSYLVANIA, ASSIGNOR TO PRESSED STEEL CAR COMPANY, OF PITTSBURGH, PENNSYLVANIA, A CORPORATION OF NEW JERSEY

DUMP CAR DOOR LOCKING MECHANISM

Application filed January 17, 1929. Serial No. 333,163.

An object of my invention is to provide an automatic door locking mechanism for the tilting body of a dump car having doors at each side, which will lock the doors in closed position when the body is horizontal, which will selectively free the descending door for opening while holding the rising door closed as the car body is tilted in dumping, and which will engage with and lock said opened door when returned to a closed position, as the car body is righted.

Another object of my invention is to provide a door locking mechanism which upon engaging with the doors of the car body will perform its locking and unlocking movements independently of the door closing mechanism.

Referring to the drawings, Fig. 1 is a transverse section through the car body showing the position of a suitable door operating mechanism and its relation to the side doors of the car body when the body is in horizontal and in final dumping positions; Figs. 2, 3 and 4 are sections through the car body and underframe along the lines 2-2, 3-3 and 4-4 of Fig. 1, this door operating mechanism forms no part of my invention but is merely an illustration of one form of mechanism which can be used with my invention; Fig. 5 is a transverse section through the dump car body and underframe embodying a preferred form of my invention. The body is shown in horizontal position by full lines and in final dumping position by dot and dash lines; Fig. 6 is a section through the door locking member along the lines 6-6 of Fig. 5 and illustrates one method of mounting the locking member on the car body; Fig. 7 is a section through the downward depending door member and shows the relation of the end of the locking member to the depending door member.

Referring now in detail to the drawings where like reference characters refer to like parts, reference character 1 indicates a dump car having a dump body 2 tiltably mounted on an underframe 3. As shown in Fig. 1 of the drawings, the body is supported on trunnions 4 having a bearing 5 on the underframe 3. However, it is to be understood that various other suitable methods may be em-

ployed for mounting the body on the underframe. At each side of the car body 2 are doors 6 which when closed form the side walls of the body. These doors 6 are hinged adjacent the floor 7 of the car body and open outwardly and downwardly as the car body is tilted for dumping. Spaced longitudinally of the doors and secured thereto are downward depending members 8, which are adapted to engage with the door operating mechanism and with the door locking mechanism. Spaced longitudinally of the underframe are suitably formed door operating mechanisms which control the opening and closing of the doors 6 as the body is tilted in dumping. Any suitable form of door mechanism can be used with my invention, and I have illustrated in Fig. 1 a preferred form which forms no part of my invention and is made the subject of an application for patent by N. S. Reeder, Serial No. 343,668, filed March 1, 1929.

The door operating mechanism comprises a member 9 mounted on the underframe and in engagement with the body, a member 10 mounted on the underframe and adapted to engage with the opening door, and a member 11 connecting with the free ends of the members 9 and 10 to cause the member 10 to be actuated by the member 9 in engagement with the tilting car body. The contour of the end of the door member 8 in engagement with the operating member 10 is such that the door is substantially closed before the body has completed its return to a horizontal position after dumping, and in this position is engaged by the locking mechanism which finally closes the doors and locks them with the return of the body to horizontal position.

The door locking mechanism, as illustrated in Figs. 5 to 7 inclusive of the drawings, comprises transverse locking bars 12 spaced longitudinally and connected to the body at the longitudinal center line thereof and in engagement with the depending door members 8-A. A method of mounting the locking bars 12 to the car body 2 is illustrated in Figs. 5 and 6 of the drawings. The longitudinal body member 13 has openings 14 therethrough in which the bar 12 is supported.

by the bearings 15, but any suitable form of bearing may be used which will serve to support the bar.

The type shown in Fig. 6 comprises a two-piece bearing attached to each side of the body member 13 and having a recess in one end for the reception of the pin 16 which is mounted in the locking bar 12. At each end of the bar 12 are mounted rotatable members 17 which bear on suitably formed surfaces on the door members 8—A. At each side of the underframe adjacent the door members 8—A are suitably formed bearings 18 which maintain the locking bar in position 15 when the body is horizontal and about which the bar 12 rotates as the body is tilted for dumping.

Adjacent the bearings 18 are suitably formed portions 19 and 19—A of the bar 12 which assist in controlling the movements of the bar 12 as the body is tilted in dumping. In cars of the type illustrated, the tilting and righting of the car body is done by body tilting cylinders mounted on the underframe 25 and operated by compressed air supplied from any available source. These cylinders form no part of the present invention and for that reason are not illustrated here but may be of any suitable form and number.

As the car body is tilted towards the right-hand side of the underframe, as illustrated in Figs. 1 and 5 of the drawings, the body rotates on its trunnions shown in Fig. 1, and by reason of the location of these trunnions 35 moves towards the right side of the underframe as the tilting continues; this causes the portion of the bar 12 at the left side of the body to leave the underframe bearing 18 with the rising of that side of the body and the portion at the right side of the body to move downwardly and to the right along the member 18 on the right side of the underframe.

This movement of the bar 12 causes the 45 portion 19—A to move onto the bearing 18 and in turn causes the bar 12 to rotate on its pin 16 to move the left side of the bar downward and the right side upward along the depending door member 8—A. The member 55 17 on the end of the bar 12 at the right side of the car moves along the surface 20 onto the surface 21 of the depending door member 8—A. The surface 21 is in the form of a depression in the member 8—A and allows the bar 12 and bearing 17 to move into the member 8—A when the door 6 opens downward by the force of gravity and the weight of the 60 lading in the car body. With the tilting of the car body the door member 8 engages with the member 10 of the door mechanism which controls the door during the subsequent movements of the body until the final dumping position is attained. The locking bar 12 during these movements of the body continues to rest on the bearing 18 and has its end bear-

ing 17 within the depression 21 of the door member 8—A which is deep enough to receive that member during all opening movements of the door. An additional depression 22 adjacent the surfaces 20 and 21 in 70 the door member 8—A allows the door to clear the bar 12 when in fully opened position. This final dumping position of the car body and relation of the bar 12 to the door member 8—A is shown in dot and dash lines on 75 Fig. 5 of the drawings and the relation of the door operating mechanism to the door member 8—A is shown on the right side of Fig. 1 of the drawings.

When the car body is returning to a horizontal position the door operating mechanism moves the door towards substantially closed position and before the body has reached a position horizontal with the underframe. The door locking bar 12 during this return 85 of the body moves along the bearing 18 and the end bearing 17 moves out of the depression 21, with a consequent rotation of the bar on its bearing 16 to bring the end bearing 17 onto the surface 20 of the door member 8—A. 90 The end bearing 17 reaches the surface 20 of the door member 8—A simultaneously with or a little before the door operating mechanism has returned the door to a substantially closed position and before the car body has completed its return to a horizontal position. 95

The door locking bar is now in contact with both depending door members 8—A and as the body completes its return to a horizontal position the bar finally closes and locks the 100 doors, and the final return movement of the body moves the door member 8 free of the door operating mechanism.

Having thus described the invention what I claim as new and desire to secure by Letters 105 Patent is:

1. The combination in a dump car of an underframe, a body tiltably mounted on said underframe, side doors for said body hinged adjacent the floor thereof, and an automatic door locking mechanism mounted on the body for locking the doors in closed position with the body horizontal, for selectively releasing the descending door for opening, and maintaining the rising door closed, as the body is tilted, for locking the opened door when returned to a closed position and means on the underframe independent of the locking mechanism for operating said doors.

2. In a dump car, an underframe, a dump body tiltably mounted on said underframe, side doors hinged adjacent the floor of said body, downward depending members on said doors, and a transverse door locking member pivotally mounted on said body having its end portions in contact with said depending door members.

3. In a dump car, an underframe, a dump body tiltably mounted on said underframe, side doors hinged adjacent the floor of said 130

- body, downward depending members on said doors, a transverse member mounted on the body and in engagement with said depending door members, bearings for said transverse member on said underframe, and suitably formed surfaces on said depending door members forming guides for said transverse body member when the body is tilted.
4. In a dump car, an underframe, a dump body tiltably mounted on said underframe, side doors for said body hinged adjacent the floor thereof, downward depending members on said doors, a transverse member pivotally mounted on said body having its extremities in engagement with said depending door members, bearings on said underframe supporting said transverse body member when the body is horizontal and suitably formed portions of said transverse body member engaging with said underframe bearing surfaces when the body is tilting.
5. In a dump car, an underframe, a body tiltably mounted on said underframe, doors for said body mounted adjacent the floor at each side thereof, a door operating mechanism mounted on the car for controlling the opening and the returning of the doors to a closed position, and a door locking mechanism pivotally mounted on the body, adjacent the underframe, and extending transversely of the body to engage with opposite doors, said locking mechanism, when in engagement with said doors, extending outwardly of the underframe beyond the door operating mechanism.
6. In a dump car, an underframe, a body tiltably mounted on said underframe, doors for said body hinged adjacent the floor thereof, downward depending members on said doors, door mechanisms mounted on the car for limiting the opening of said doors with the tilting of the body and the returning of the doors to a closed position when the body is righted, a member pivotally mounted on the body and extending transversely thereof for engagement with the downward depending member of opposite doors, said transverse member having portions adjacent each end thereof offset from the major portion of the member, said offset portions engaging with the underframe when the body is tilted to control the engagement of the transverse member with the unopened door.
7. In a dump car, an underframe, a body tiltably mounted on said underframe, doors for said body hinged adjacent the floor thereof, downward depending members on said door, door operating mechanism mounted on the car for limiting the opening of said doors with the tilting of the body and returning said doors to a closed position as the body is righted, a member pivotally mounted on the body and extending transversely thereof for engagement with downward depending members of the doors on opposite sides of the body,
- offset portions adjacent each end of said transverse member engaging with the underframe at the side towards which the body is tilting, said offset portions moving the end of the transverse member in engagement with the inactive door longitudinally of the depending member of said door.
8. In a dump car, an underframe, a body tiltably mounted on said underframe, doors hinged adjacent the floor thereof, downward depending members on said doors, mechanism mounted on the underframe for controlling the movements of said doors during the tilting and righting movements of the body, a member pivotally mounted on the body and extending transversely thereof for engagement with said doors, said transverse member engaging with the underframe adjacent each side thereof for holding the door on the opposite side of the body in closed position.
9. In a dump car, an underframe, a body tiltably mounted on said underframe for dumping to either side thereof, side doors for said body hinged adjacent the floor thereof, a plurality of downward depending members on said doors spaced longitudinally thereof, a mechanism mounted on the underframe for controlling the movement of the door at the discharging side of the body during the tilting and righting movements of the body, a member mounted on the body and extending transversely of the underframe to each side thereof to engage with the adjacent downward depending members when the doors are in closed position and a member mounted on each side of the underframe in engagement with said transverse member, said transverse member moving transversely of said underframe member to release the descending door for opening as the body moves in dumping.
10. In a dump car, an underframe, a body tiltably mounted on said underframe, doors for said body hinged adjacent the floor thereof, and door operating mechanism for controlling the opening and closing movements of the discharging door as the body is tilted, and a door locking member pivotally mounted on the body and extending transversely thereof to engage with the opposite doors, said member holding said doors in closed position independently of the door operating mechanism when the body is in load carrying position and releasing the doors for opening movement when the door is engaged by the adjacent portion of the door operating mechanism as the body is tilted.

JOHN P. ANDERSON.
